UNITED STATES PATENT OFFICE

90,619

DESIGN FOR A BOTTLE

Jack F. Infield, Los Angeles, Calif., assignor to
California Consolidated Water Company, Los
Angeles, Calif., a corporation of Delaware

Application June 5, 1933. Serial No. 48,271

Term of patent 14 years

To all whom it may concern:

Be it known that I, JACK F. INFIELD, a citizen of the United States, residing in the city of Los Angeles, county of Los Angeles, State of California, have invented a new, original, and ornamental Design for a Bottle, of which the following is a specification, reference being had to the accompanying drawing, forming part thereof.

In the drawing:

Fig. 1 is a front elevation and
Fig. 2 is a side elevation of a bottle showing
my new design.

I claim:

The ornamental design for a bottle, as shown.
Signed at Los Angeles, California, the 16th day
of May, 1933.

JACK F. INFIELD.
